UNITED STATES PATENT OFFICE.

WARREN McARTHUR AND WARREN McARTHUR, JR., OF CHICAGO, ILLINOIS.

DESIGN FOR A TUBULAR LANTERN.

45,265.

Specification for Design.

Patented Feb. 17, 1914.

Application filed November 22, 1913. Serial No. 802,552. Term of patent 14 years.

To all whom it may concern:

Be it known that we, WARREN McARTHUR and WARREN McARTHUR, Jr., citizens of the United States, residing at Chicago, in the county of Cook and State of Illinois, have invented a new, original, and ornamental Design for Tubular Lanterns, of which the following is a specification.

The accompanying drawing represents an elevation of a tubular lantern embodying this design.

The characteristic feature of this design consists of a flame chamber which has a

downwardly tapering peripheral wall A and a flat top B which extends from the upper end of the peripheral wall inwardly in a substantially horizontal direction to a chimney C which rises centrally from this flat top.

We claim:

The ornamental design for a tubular lantern as shown and described.

WARREN McARTHUR.

WARREN McARTHUR, JR.
